BY *Victor J. Evans*

ATTORNEY

UNITED STATES PATENT OFFICE

JOHN CAL REEDER, OF OKLAHOMA CITY, OKLAHOMA

TOY AEROPLANE

Application filed August 29, 1928. Serial No. 302,810.

My present invention has reference to an amusement device for children and my object is the provision of a toy aeroplane in which one or more children may be seated 5 and caused to travel by the gravitating of the plane on an overhead track which has its ends adjustably secured between two spaced posts, there being buffer means between the aeroplane and the posts at the lower end of the track, and likewise being means whereby the child can cause the aeroplane to travel backward or to its initial position onto the track.

A further object is the provision of an 15 amusement device for this purpose that is characterized by simplicity in construction, cheapness in manufacture, ease in erection and which will be perfect in operation.

To the attainment of the foregoing the 20 invention consists in the improvement as hereinafter described and definitely claimed.

In the drawings:

Figure 1 is a side elevation of the improvement.

25 Figure 2 is an approximately central vertical longitudinal sectional view through the toy aeroplane.

As disclosed by Figure 1 of the drawings, I erect a platform 1 that has steps 2 leading thereto. At the rear of the platform there is a post 3 that projects a suitable distance above the platform. In a line with the post 3, but at a distance therefrom, I erect a second post 4. The post 4 is of a less 35 height than the post 3. Passing through suitable openings adjacent to the top portions of each of the posts 3 and 4 there are eye bolts 5 which are engaged by nuts 6 and to these eye bolts I secure the ends of 40 a wire track or cable 7.

The post 4 has angle braces 8 secured between the same and the ground surface, and between these posts there is an upwardly directed curved flat buffer spring 9.

45 The toy aeroplane 10 may be constructed of any desired material, but is shaped to simulate a regular aircraft, the same being provided with a tail, a rear rudder, transverse planes or wings and the landing wheels 11. The top of the plane is also provided

with an opening leading to the cock-pit 12 therein and in this cock-pit the child or children are seated. The body of the aeroplane is provided, adjacent to its front, at a suitable distance from its rear, with upstanding standards 13, each of the same preferably having its outer end bifurcated and in these ends there are journaled the shafts for grooved wheels 14. As the bifurcated ends of the standards 13 straddle the track 7 and as the grooved rollers 14 are arranged on the track, it will be obvious that the body 10 cannot be accidentally moved off of the track. Further it will be apparent that because of the inclination of the track the body 10 will travel by gravity on the platform 1 to the post 4.

Fixed, preferably in one of the bearings 13 and in the front of the body 10 there is an axle 15. This axle has an outer headed end whose face is rounded, as at 16, and this end provides a bumper. Freely mounted for rotation on the axle 15 there is a propeller wheel 17. The currents of air contacting with the blades of the wheels 17 will cause the same to rotate in the travel of the craft from the platform 1 to the post 4, and the bumper 16 will contact with the spring buffer 9 to prevent jar between the craft 10 and the post 4. As a matter-of-fact, the 55 spring buffer 9 will cause the body 10 to be moved for a certain distance in a retrograde direction, and will for a considerable length of time cause a reciprocatory movement of the body 10 on the track. As stated, the inclination of the track 7 is slight so that the body 10 will travel at a comparatively slow speed between the platform 1 and the post 4. Also the ground surface, at suitable 60 points between the platform 1 and the post 4 is raised or rounded, as at 18, so that the landing wheels will contact with this part of the ground surface and slightly elevate the body 10 to bring the grooved wheels 14 off of the track, the momentum of the body 65 being sufficient to permit of such travel over the rounded or ground surface or mound 18. The post 3 has attached thereto one end of a chain or like flexible element 70 75 80 85 90 95 100

18', and the operator will draw upon this

element to return the body 10 to the platform 1 and can hook or tie the cable to prevent the movement of the body on the track 7 when the child or children are placing themselves in or removing themselves from the body.

If desired the posts at the starting station and landing station may be of the same height, so that the cable 7 will have its ends attached to these posts at the same elevation. The cable 7, however, is slackened and, therefore, bows downwardly at the part thereof on which the toy is arranged, especially by the weight of the occupants in the body of the car. The occupant may exert a pressure upon the toy so as to bring the wheels into contact with the ground should he so desire or the device may travel so that the wheels will not engage with the ground.

Having described the invention, I claim:

1. In an amusement device for the purpose set forth, spaced posts, an inclined track secured to the posts, a body having standards which are bifurcated to receive the track therebetween, grooved wheels journaled in the bifurcated portions of the standards and arranged for travel on the track, a bumper on one end of the body and a spring buffer on the post at the lower end of the track and in the path of contact with the bumper.

2. A child's amusement device comprising a pair of spaced posts, a platform erected at one of the posts, eye bolts passing through the posts and disposed one above the other, adjustable elements screwed on the eye bolts, a cable track having its ends fixed to the eye bolts and arranged at an inclination, a body shaped to represent an aeroplane, standards arising from the body and having bifurcated outer ends, to receive the cable track therebetween, grooved wheels journaled in the bifurcated ends of the standards for travel on the track, landing wheels on the body, an axle fixed on the front end of the body and having a rounded head that provides a bumper, a wind wheel freely journaled on the axle, and a spring buffer on the post at the lower end of the track and in the path of contact with the bumper.

3. A child's amusement device comprising a pair of spaced posts, a platform erected at one of the posts, eye bolts passing through the posts and disposed one above the other, adjustable elements screwed on the eye bolts, a cable track having its ends fixed to the eye bolts and arranged at an inclination, a body shaped to represent an aeroplane, standards arising from the body and having bifurcated outer ends, to receive the cable track therebetween, grooved wheels journaled in the bifurcated ends of the standards for travel on the track, landing wheels on the body, an axle fixed on the front end of the body and having a rounded

head that provides a bumper, a wind wheel freely journaled on the axle, and a spring buffer on the post at the lower end of the track and in the path of contact with the bumper, and a flexible element secured to the post next to the platform and coiled into the cock pit of the toy aeroplane.

4. A child's amusement device comprising a pair of spaced posts, a platform erected at one of the posts, eye bolts passing through the posts and disposed one above the other, adjustable elements screwed on the eye bolts, a cable track having its ends fixed to the eye bolts and arranged at an inclination, a body shaped to represent an aeroplane, standards arising from the body and having bifurcated outer ends, to receive the cable track therebetween, grooved wheels journaled in the bifurcated ends of the standards for travel on the track, landing wheels on the body, an axle fixed on the front end of the body and having a rounded head that provides a bumper, a wind wheel freely journaled on the axle, a spring buffer on the post at the lower end of the track and in the path of contact with the bumper, and a flexible element secured to the post next to the platform and coiled into the cock pit of the toy aeroplane, and the ground surface between the posts being formed with a mount over which the landing wheels of the toy aeroplane are designed to travel.

In testimony whereof I affix my signature.
JOHN CAL REEDER.
